UNITED STATES PATENT OFFICE

166,009

PARKING METER

William N. Woodruff, Cincinnati, Ohio, assignor
to The Herschede Hall Clock Company, Cincinnati,
Ohio, a corporation of Ohio

Application November 13, 1950, Serial No. 12,941

Term of patent 14 years

(Cl. D52—3)

To all whom it may concern:

Be it known that I, William N. Woodruff, a citizen of the United States of America, residing at Cincinnati, Hamilton County, State of Ohio, have invented a new, original, and ornamental Design for a Parking Meter, of which the following is a specification, reference being had to the accompanying drawing, forming a part thereof.

In the drawing:

Figure 1 is a view in front elevation of a parking meter, showing my new design;

Fig. 2 is a view in side elevation of the parking meter; and

Fig. 3 is a view in rear elevation of the parking meter.

In the drawing the essential features are shown in full lines and by shading.

I claim:

The ornamental design for a parking meter, as shown and described.

WILLIAM N. WOODRUFF.
